UNITED STATES PATENT OFFICE

JOHN J. CAVAGNARO, OF RIDGEWOOD, NEW JERSEY

PRESS

Application filed July 16, 1930. Serial No. 463,431.

My invention relates to presses used principally for embossing or otherwise acting upon a web of material, such as artificial leather or similar fabric, which is fed in a series of steps between the press platens which are moved apart mechanically to permit forward movement of the web, and are forced together by hydraulic pressure to grasp the web and impress the pattern of an engraved plate therein. In such a press the platens have to be moved apart a considerable distance to permit the forward feeding of the web; whereas the actual embossing operation while it necessitates the application of excessive pressure to the web, is accompanied by slight movement of the press platens toward one another.

More specifically stated, my invention relates to presses for the purpose mentioned and wherein the movement of the platens apart to permit forward feeding of the web and back toward and into or nearly into engagement with one another, is accomplished by mechanical means, and rapidly and during a short part of the cycle of operation of the press; while the actual pressing operation after the platens have grasped the web between them is due to hydraulic pressure acting throughout a comparatively long time. Each cycle of operation of such a press is therefore made up of a comparatively long application of great pressure to the web by hydraulically operated means followed by a comparatively short part which is produced by mechanical devices, and during which the press is opened and the web is moved forward to receive another impression thereupon. The part of the cycle which consists in the pressing of the web by hydraulically operated means after the press has been closed is therefore several times as long in time as the mechanically operated part of the cycle, during which the press is opened and closed and the feeding of the web takes place.

In my improved press the mechanical and the hydraulic operations are entirely independent of one another, except that the mechanical phase is produced by a rotating main operating cam and the hydraulic phase is controlled by a valve device which is operated

by the same cam. This permits the mechanical and hydraulic elements of the press to be designed each independent of the other and with reference to what each is to accomplish; and the two to be co-related with reference to the speed of operation of the press, the desired duration of the mechanical and hydraulic phases of the cycle, and otherwise with reference to the work which the press is to do.

The drawings accompanying and forming a part of this application illustrate the preferred form of my invention, although the same may be embodied in other forms; and I regard my invention as including all such variations and modifications of the particular form thereof illustrated and hereinafter described and explained as come within the scope of the concluding claims, wherein the features wherein my invention consists are particularly pointed out.

In the drawings wherein like reference numerals designate the same parts in the several views:

Figure 1 is a view showing my improved press in elevation, and as seen from a position toward which the web operated upon is being fed. In this view the central part of the press is omitted so that the two ends thereof may appear in a single view.

Figure 2 is a view showing the press as seen from the left hand end thereof, referring to Figure 1.

Figure 3 is a view showing the press in plan, as seen looking down from a horizontal plane indicated by the line 3-3, Figure 1; parts at upper levels being broken away in part to give a better understanding of the appearance, in plan, of parts below them.

Figure 4 is a fragmentary sectional view upon a larger scale, and upon a vertical plane indicated by the line 4-4, Figure 3, looking to the right, of the lifting and supporting mechanism for the lower platen of the press.

Figure 5 is a similar view showing the parts shown in Figure 4 in other positions, the platen being up in Figure 5 and down in Figure 4.

Figure 6 is a fragmentary view showing parts at the left hand end of Figure 1 and

the right hand side of Figure 2, the parts for the most part being the ones illustrated in Figures 4 and 5.

Figure 7 is a fragmentary view taken upon 5 a vertical plane indicated by the line 7-7 of Figure 6.

Figure 8 is a view showing one of four cams for lifting the upper platen, the view being as seen from a vertical plane indicated 10 by the line 8-8, Figure 6.

Figure 9 is a view showing the parts shown in Figure 8, looking down from a horizontal plane indicated by the line 9-9 of Figure 8.

Figure 10 is a view showing the main operating cam, the valve device for controlling the hydraulically operated parts, and other adjacent and related parts of the press, the same being as seen from a vertical plane indicated by the line 10-10, Figure 11.

20 Figure 11 is a view showing the parts shown in Figure 10, as seen from planes indicated by the broken line 11-11, Figure 10.

Figure 12 is a view showing the port and 25 valve feature of the valve device for controlling the hydraulically operated parts of the press.

Figure 13 is a fragmentary view showing another form of mechanically operated mechanism for lifting and lowering the lower platen and supporting it during the hydraulic pressing part of the cycle of the press.

Referring now to the drawings, my improved press has a lower head 15 and an upper head 16 held at a fixed distance apart by four columns or standards 17, which resist the stresses due to the operation of the press. The upper surface of the lower head provides a horizontal flat surface of large area, and 40 resting thereupon are two cylinders 18 to which oil or equivalent liquid is supplied under high pressure during the hydraulic phase of the cycle of operation of the press. In Figure 1 the central parts of the heads and the 45 inner halves of both cylinders are broken away so that both ends of the press where most of the operating mechanism is located will appear in a single view; while the plan view Figure 3 shows the lower head entire 50 and the relation of width to length, in the direction of travel of the web operated upon, of a press actually built.

Vertically movable in the cylinders 18 are 55 pistons 19 having cup leather or other form of packing 20 suitable for liquids under high pressure, at their lower ends; and the numeral 21 designates a vertically movable hydraulically operated ram member which rests upon the upper ends of the pistons and is 60 lifted by them during the pressing operation; the movement of the yoke and the parts carried thereby due to fluid under pressure supplied to the cylinders, however, being slight as compared with the movement imparted to the lower platen by me-

chanical means to close and open the press, as will hereinafter appear. The ram member is provided with depending pins 22 which enter holes in the pistons to keep the ram in proper position upon the pistons, and suitable removable stops 23 having set screws 24 rest upon the lower head, and serve to adjust the cylinders upon the upper flat surface thereof and position the ram member and the parts carried thereby properly in the press. The pins 22 are of such length below the under surface of the ram member that the ram may be held up, as by wooden struts, placed between it and the upper side of the lower head, and the pistons permitted to descend independently of the ram member; whereupon and after removing the stops 23 the cylinders with the pistons in them may be moved sidewise and removed from the press.

The upper surface of the ram member 21 (which as will be appreciated extends from one side of the press to the other, Figure 3, and takes up substantially all the space between the columns 17) is inclined upward 90 from its front and rear edges toward its center, as shown in Figures 2, 4 and 5, where it is highest; and above the ram member and movable vertically relative thereto is the lower platen 25. The upper fixed platen is secured to the under side of the upper head 16 and is indicated, conventionally, by the numeral 26; and it is commonly provided with internal passages so that it may be heated by steam. The upper and lower platens carry the usual engraved plate and matrix, 95 the usual backing plates, and whatever other parts may be necessary to produce the desired pressing action upon the web operated upon. These parts will vary with different web materials, patterns to be impressed thereupon, etc., and they are not described in detail as they form no part of this present invention.

The web or fabric to be embossed or otherwise operated upon is fed between the platens 110 when they are apart; and after the lower platen has been raised by mechanically operated means to bring the platens together with the web between them, hydraulic pressure is applied through the ram member to impress the pattern or design in the web, as will be understood. The lower platen 25 is guided in its movement toward and from the upper platen by suitable guides, preferably in the form of pins 27, depending from the upper platen and extending through bearings in ears 28 at the sides of the lower platen, to thereby secure more perfect registration of the engraved plate and matrix which cooperate to impress the design in the web being operated upon. The lower platen is moved rapidly upward and away from the ram member (and preferably downward also, although its downward movement may be by gravity) by positively acting mechanical 125 130

means, and throughout a comparatively great distance; its uppermost position being shown in Figure 5 (and in 6 and 7 also), and its lowermost position the best in Figure 4.

After the lower platen has reached its uppermost position it is supported by wedge-shaped transversely movable supporting members operating in between the inclined upper surfaces of the ram member 21 and the under side of the platen; and thereafter and throughout the greater part of each cycle of operation fluid under pressure is supplied to the cylinders 18, and pressure sufficient to emboss the web is applied to the lower platen through the pistons 19, ram member 21, and wedge-shaped supporting members mentioned. The downward movement of the lower platen provides sufficient space between the platens to permit the convenient feeding forward of the web, and its following upward movement brings it into approximate contact with the web. These are movements of comparatively large magnitude and are produced by mechanical means; whereas the hydraulically operated parts of the press produce but slight movement of the lower platen, as the platens are then close together with the web grasped between them.

In order to accomplish the positive mechanical lifting of the lower platen the four corners thereof are provided each with a lifting member, preferably in the form of a cam, all four of which act simultaneously to lift the platen. These cams are indicated all by the numeral 29 and they are connected with the platen through bolts 30 which permit a slight pivotal movement of the cams. Preferably there are brackets 31 at the corners which are fastened to the platen by cap screws 32, see Figures 6, 8 and 9, which brackets form the immediate supports for the cams; and these brackets are provided with abutments 33 between which and the cams springs 34 are placed, the positions of the cams being adjustable by bolts 35, one of which appears in detail in Figure 8. These springs are so stiff that they act as non-yielding members through which the lower platen is lifted to bring it into contact with the web; but they will yield to prevent injury to the lifting mechanism, as will hereinafter appear, during such slight movement as occurs while the hydraulically operated parts are operating to emboss the web.

The lifting members 29 are provided with grooves 36 in their inner sides; and 37, 38, see Figure 2, designate oscillating lifting levers which are supported by bolts 39, 40 carried by the ram member 21, so that the levers move with said ram member. The upper ends of the levers have rollers 41 which travel in the grooves 36; and an upwardly extending arm 42 of the right hand lever is connected with the lower end of the lever 37 at the left so that the upper ends of the

levers and their rollers move simultaneously toward and from one another, by an adjustable link member 43. This lower platen lifting mechanism is duplicated at each side of the press, see Figures 1 and 3, so that all four corners of the platen are lifted simultaneously, as will be understood. The outer parts of the cam grooves 36 are inclined and their inner parts are horizontal, as illustrated, so that lifting of the upper platen occurs while the rollers 41 move along the inclined parts of the grooves; after which the rollers may move along the horizontal parts of the grooves to a greater or less extent without lifting the platen. The lower ends of the levers 38 are pivotally connected through adjustable substantially horizontally disposed links 44 with the upper ends of the arms 45 which are carried by an oscillating shaft 46, which extends from side to side of the press, see Figure 3, and which shaft is supported in bearings in brackets 47 extending from the lower head 15 which serve also to support feeding mechanism for the web; which mechanism, however, is not illustrated as the same forms no part of the invention to which this present application relates. The shaft 46 is oscillated by an arm 48 having a roller 49 at its lower end which runs in a cam groove 50 in the outer side of a rotating main operating cam 51 located at the left side of the press, see Figures 1 and 3, and which cam operates the upper platen lifting mechanism above described. This cam also operates a valve device for controlling the supply of liquid under pressure to the cylinders 18 to operate the pistons 19 and ram member 21, wherefore as will be appreciated the mechanically and hydraulically operated parts are operated in proper sequence to carry out the cycle of operation of the press.

The cam groove 50 is circular throughout somewhat more than three-quarters of its length, and has a shorter portion of somewhat less than one-quarter of its length which is displaced toward the center of the cam; so that the lifting mechanism is operated to lift the lower platen while the portion —A, B— of the groove moves past the roller 49. Then as the circular part from —B to C— moves past the roller the platen is supported in its uppermost position, during which part of the cycle hydraulic pressure acts to emboss or otherwise act on the web; and finally and throughout the part —C, A— of the groove the platen is lowered and returns to the lowermost position in which it is shown in Figure 2. During the somewhat more than three-fourths of each complete rotation of the cam 51 while the portion —B, C— of its groove is moving past the roller 49 the lower platen is being supported in its uppermost position by supporting plates; and throughout this long part of the cycle hydraulic pressure within

the cylinders 18 is communicated to the lower platen through the pistons 19, the ram 21, and the said supporting plates and the embossing of the web is accomplished. These supporting plates, see Figures 2 and 4 to 6, are shown as wedge-shaped in form and as resting upon and supported by the ram member 21; and they extend, see Figure 1, throughout the length of the ram member. They are designated by the reference numerals 52, 53, and are obviously arranged in between the upper end of the ram member and the under side of the lower platen and move upon the inclined upper surfaces of the ram member. The supporting plates 52, 53 are moved toward and from one another and transverse to the ram member by the same mechanism which lifts the lower platen, so that upward movement of the platen and inward movement of the supporting plates occurs simultaneously; movement being communicated to the plates by inward extensions of the pins 54 which are at the upper ends of the levers 37, 38 and which support the rollers 41; see Figure 6, said extensions entering bushed holes in the sides of the supporting plates adjacent their outer corners as shown. The inner edges of the supporting plates, see Figures 2, 4 and 5, are shown as provided with hardened steel plates 55, the outer ends of which slide upon hardened steel plates 56 secured to the sides of the ram member 21, to thereby lessen the wear upon the ram member, which is commonly made of cast iron, due to the movement of the plates upon the inclined upper surface thereof. These wear plates engage one another at the end of the movement of the supporting plates toward one another; and at the end of such movement the inner ends of the supporting plates abut against upwardly extending projections 58 of the pins 22, these being located inward a considerable distance from the sides of the ram member and lower platen as will be appreciated. The under side of the lower platen has recesses into which the projections 58 extend when the platen is in its lowermost position, as shown in Figures 4 and 5.

The supporting plates 52, 53 are shown as cored out in their under sides to lighten them; and on their upper sides they are provided with a plurality of upwardly extending supporting ribs 59 extending parallel with one another and throughout the lengths of the plates, see Figures 3, 4 and 5. The under side of the lower platen 25 has similar depending supporting ribs 60 which lie alongside the ribs 59 when the lower platen is down and the supporting plates are in their outer positions shown in Figures 2 and 4. When the platen has been lifted, however, and when the supporting plates have been moved into their innermost posi-

tions shown in Figures 5, 6 and 7, the ribs 59 will lie directly beneath the ribs 60 thereby providing a positive and unyielding support for the lower platen throughout substantially its entire area. This position of the parts is attained when the part —B— of the cam groove 50 reaches the roller 49, see Figure 2, and thereafter and while the roller is in the part —B, C— of the groove of constant radius hydraulic pressure will be communicated to the lower platen to emboss the web as hereinbefore explained.

There will or may be some slight space between the ends of the ribs 59, 60 in the position in which they are shown in Figures 5, 6 and 7, as some clearance is desirable in order to permit the ribs 59 to move beneath the ribs 60, although it may be reduced to the vanishing point by beveling the extremities of the ribs; and the springs 34, which are stiff enough not to yield under the weight of the platen 25 but will yield under hydraulic pressure, are provided to prevent the transmission of the excessive pressure during the embossing of the web to the rollers 41, which are then in the horizontal parts of the cam grooves 36, and to other parts of the mechanism which lifts the lower platen and moves the supporting plates.

The construction of the lower platen and the supporting members therefor illustrated and described permits the platen to be made unusually light in weight for a member of large area and which has to be subjected to hydraulic pressure, often of several hundred pounds per square inch, so that it can be moved rapidly and with little expenditure of power as the inertia and momentum to be overcome are not great; and at the same time provides a scheme wherein the platen is supported throughout substantially its entire area from the massive ram member of the press during the part of the cycle of operation thereof when hydraulic pressure is being applied to the web to accomplish the embossing, pressing, or like operation performed thereupon.

Fluid under pressure is supplied to the cylinders 18 to accomplish the embossing of the web while the lower platen is supported in its uppermost position as aforesaid from an accumulator or equivalent source of high pressure through a pipe 61 leading into the casing of a controlling valve device 62, from which device piping 63 leads to the cylinders; which piping serves also to permit the flow of fluid from the cylinders and from the valve device through a waste pipe 64.

The internal port and valve arrangement of the controlling valve is illustrated in Figure 12 wherein the numeral 65 designates the supply and 66 the release or waste valve. These are operated by a single pivotally supported oscillating lever 67; and springs beneath the valves keep them both normally

closed and the lever in its central position. When the lever is moved to the right the supply valve 65 is opened and liquid under high pressure flows through the piping 63 to the cylinders, and when the lever is moved to the left the waste valve 66 is opened and pressure in the cylinders is relieved and a small quantity of liquid may pass from the cylinders through the piping 63 and waste pipe 64. A roller 68 is provided on the lever 67 for moving the same first in one direction and then in the other from its central position; and the lever also serves as a handle whereby the waste valve 66 may be opened manually when the lower platen is down and the press is open, to thereby permit further downward movement of the pistons and ram member and a separation of the platens to a greater extent than they are normally apart when the press is open so that the embossing plates may be removed and changed. The lever 67, however, can be operated manually only when the lower platen is down, and the press is open, and can never be operated to open the supply valve 65. The valve device is operated by a cam groove 69 in the rear or right hand surface of the main cam member 51 into which groove the roller 68 of the lever 67 extends and within which it lies. Obviously the supply valve 65 should be opened and pressure applied to the lower platen as soon as practicable after the same has been moved into its uppermost position and the supporting members have been moved into the supporting positions in which they are shown in Figure 5; and this opening occurs when an inclined part of the inner side wall of the groove 69 at the point —D— passes the roller 68. The supply valve after having been opened remains open while the portion from —D— to —E— of the cam groove, which is of constant radius, moves past the roller 68; and hydraulic pressure is applied to the lower platen and to the web during this comparatively long part of the cycle produced by each complete rotation of the main cam 51.

The part —E— of the cam groove 69 reaches the roller 68 about the time the part —C— of the cam groove 50 reaches the roller 49; and as the main cam continues its rotation a projection 70 from the outer side wall of the groove 69 engages the roller 68 and swings the lever 67 to the left, thus permitting the supply valve 65 to close and opening the waste valve 66 and relieving the pressure within the cylinders 18. Then and as the cam rotates further the part —C— of the groove 50 moves past the roller 49, the supporting plates are moved from the positions in which they are shown in Figure 5 into the positions shown in Figure 4, and the platen 25 descends and resumes its lowermost position shown in Figure 2.

The opening of the waste valve 66 is of short

duration as it is necessary only that the hydraulic pressure to which the lower platen is subjected be relieved. There is therefore a minimum of waste of the high pressure liquid and very little of it flows through the waste pipe 64 and, while there is or may be some downward movement of the pistons in the cylinders, such movement is of slight extent.

The portion of the groove 69 between the points —E— and —D— is widened inward, as shown. This allows the lever 67 to be moved to the left and the waste valve 66 opened, thus permitting the pistons, the ram member and lower platen to descend as is necessary when the embossing plates are to be removed from the press; although if the ram member is kept from descending as by suitable struts between it and the lower head, then the pistons alone descend and when their upper ends are clear of the lower ends of the pins 22 the cylinders with the pistons in them may be moved sidewise and removed from the press. The outer side wall of the wide part —E, D— of the groove 69 lies close to the roller 68 so that while the waste valve 66 may be opened manually when the press is open, it can be opened at no other time. The supply valve 65 can never be opened manually because movement of the lever 67 to the right is prevented by the outer side wall of the widened part —E, D— of the groove 69 which acts as a stop for the roller 68 when the press is open; while at other times the roller fills the entire width of the groove and prevents movement of the lever.

The main cam 51 determines the cycle of operation of the press and in addition to operating the platen lifting and supporting mechanism and the valve device which controls the supply of liquid under pressure to the cylinders as hereinbefore explained, it has another cam groove in its inner side and a peripheral ridge 71, both concerned with the feeding of the web operated upon which feeding mechanism, however, is not illustrated as it forms no part of this present invention. The main cam is supported upon a short supporting bearing or pin 72 carried by a bracket 73 attached to the lower head 15, and is fastened to a gear 74 by bolts 75 and pins 76 or otherwise, so that the gear serves to drive the cam. This gear 74 is driven from a main driving shaft 77 which is rotatable in a bearing in the bracket 73 through a pinion 78 on the end of the shaft and an idler gear 79, see Figure 10; and the numerals 80, 81 designates similarly shaped plates, the former being fastened to the bracket 73 by a bolt 82 so as to be in effect a part thereof. The plate 81 is spaced apart from the plate 80 and the two plates are held together by bolts 83 having shoulders for spacing the plates the proper distance apart; and 79 designates an idler gear which is carried by a short shaft, the

ends of which are supported in oppositely located bearings in the plates 80, 81. Other pairs of bearings 84, 85, as many as may be required, are provided for supporting other idler gears; so that a different main cam, driving gear, idler gear and pinion than those illustrated may be substituted for the ones illustrated. This permits other main cams similar to the cams 51 but wherein the duration of the platen lifting and supporting phase of the cycle, and of the part of the cycle during which hydraulic pressure is applied to the lower platen, are different than with the cam 51 illustrated, to be used in place of the said cam; and provides also for varying the speed of rotation of the main cam and the duration, therefore, of the cycle of the press.

The right hand end of the main driving shaft 77 is supported in a bearing in a bracket 86 supported by the lower head 15; and this shaft is driven by a gear 87 fast thereon. Meshing with the gear 87 is a pinion 88 which is freely rotatable on a shaft 89, but which pinion may be clutched to the shaft by a clutch 90 so that the main shaft 77 will be driven from the shaft 89 through the pinion 88 and gear 87. The shaft 89 is driven by a gear 91 fast thereon, and this gear is in turn driven by a pinion 92 upon the right hand end of a motor shaft 93 extending from an electric motor 94 which serves to drive the press, and motor 94 is driven by a belt and pulley.

The reference numeral 95 designates a roller which is supported by adjustable arms 96 which are pivotally attached to the platen 25 through the bolts 30 which fasten the left hand lifting members 29 to the platen; the purpose of said roller being to hold the entering end of the web up and away from the left hand edge of the lower platen when it is down, and the web is being fed forward between the platens.

In the form of my invention thus far described a separate and distinct mechanism is provided for lifting and lowering the lower platen, and the wedge-shaped platen supporting members have nothing to do with the lifting of the said platen. Figure 13, however, illustrates a form of my invention wherein wedge-shaped members 97 rest and move upon inclined upper surfaces of a ram member 98 similar to the ram member 21; and which members are mechanically operated by oscillating levers 99, 100 carried by the ram member, and which are operated from a main operating cam in substantially the same way as in the form of my invention hereinbefore described.

In this form the members 97 act to lift the lower platen 101 and also to support the same in its uppermost position; and in order to increase the lifting effect of single pairs of cooperating wedge-shaped surfaces, like the under sides of the members 97 and the in-

clined upper surfaces of the ram member, the members are shown inclined upon their upper sides also, and the lower platen as having inclined surfaces upon its under side.

When hydraulic pressure is transmitted through the lifting and supporting members 97 to the lower platen 101 in this form of my invention there is some tendency of the members 97 to move outward, because of the outwardly acting components of the forces which are transmitted to the lower platen; but the operating mechanism may be so designed as to prevent such movement, especially when conditions permit the use of lifting members having single pairs of cooperating wedge surfaces (in which case the upper surfaces of the lifting members and the under side of the lower platen are horizontal surfaces) or of lifting members the inclined surfaces of which are at sufficiently acute angles to the horizontal. Both these conditions may be otherwise expressed by saying that when the lifting of the lower platen does not have to be great then the parts may be readily designed so that the lifting members will have little or no tendency to move outward when pressure is applied to the lower platen, this being especially so in cases where the pressure applied to the web in pounds per square inch does not have to be great as hydraulically applied pressures are commonly thought of.

Having thus described my invention and explained the operation thereof, I claim and desire to secure by Letters Patent:

1. In a press of the class described, a vertically movable hydraulically operable ram member; a valve device for controlling the movement of said ram member; a lower platen arranged above and movable relative to said ram member; a fixed upper platen arranged above said lower platen; mechanically operated means carried by and movable relative to said ram member for supporting said lower platen in its uppermost position and transmitting force thereto from said ram member, and for permitting movement of said lower platen toward said ram member and into its lowermost position; and a cam member adapted to operate said lower platen, said mechanically operated means and said valve device.

2. In a press of the class described, a vertically movable ram member; a lower platen arranged above and movable relative to said ram member; a fixed upper platen arranged above said lower platen; and mechanically operated supporting members carried by and movable transverse to said ram member for supporting said lower platen in its uppermost position and transmitting force thereto from said ram member, and for permitting movement of said lower platen toward said ram member and into its lowermost position.

3. In a press of the class described, a ver-

- tically movable hydraulically operable ram member; a lower platen arranged above and movable relative to said ram member; a fixed upper platen arranged above said lower platen; and mechanically operated wedge-shaped supporting members carried by said ram member and movable transverse thereto toward and from one another between said ram member and said lower platen for supporting said lower platen in its uppermost position and transmitting force thereto from said ram member; and for permitting movement of said lower platen toward said ram member and into its lowermost position.
4. In a press of the class described, a vertically movable hydraulically operable ram member; a fixed upper platen; a vertically movable lower platen arranged between said ram member and said upper platen; mechanically operated means carried by said ram member for moving said lower platen upward and away from said ram member; and mechanically operated supporting members located between said ram member and said lower platen and movable into positions to support said lower platen in its uppermost position, and to permit downward movement thereof into its lowermost position.
5. In a press of the class described, a vertically movable hydraulically operable ram member; a fixed upper platen; a vertically movable lower platen arranged between said ram member and said upper platen; mechanically operated means carried by said ram member for moving said lower platen upward and away from said ram member; and mechanically operated wedge-shaped supporting members located between said ram member and said lower platen and movable transverse to said ram member into positions to support said lower platen in its uppermost position, and to permit downward movement thereof into its lowermost position.
6. In a press of the class described, a vertically movable hydraulically operable ram member; a fixed upper platen; a vertically movable lower platen arranged between said ram member and said upper platen; a wedge-shaped supporting member located between said ram member and said lower platen and movable transverse to said ram member into positions to support said lower platen in its uppermost position, and to permit downward movement thereof into its lowermost position; and mechanically operated means for simultaneously moving said lower platen upward and away from said ram member and said wedge-shaped supporting member transverse to said ram member.
7. In a press of the class described, a vertically movable hydraulically operable ram member; a fixed upper platen; a vertically movable lower platen arranged between said ram member and said upper platen; wedge-shaped supporting members located between said ram member and said lower platen and movable toward and from one another transverse to said ram member and into positions to support said lower platen in its uppermost position, and to permit downward movement thereof into its lowermost position; and mechanically operated means for simultaneously moving said lower platen upward and away from said ram member and said wedge-shaped supporting members transverse to said ram member.
8. In a press of the class described, a vertically movable hydraulically operable ram member; a fixed upper platen; a vertically movable lower platen arranged between said ram member and said upper platen; wedge-shaped supporting members carried by said ram member and located between said ram member and said lower platen, and movable toward and from one another transverse to said ram member into positions to support said lower platen in its uppermost position, and to permit downward movement thereof into its lowermost position; and mechanically operated means carried by said ram member for simultaneously moving said lower platen upward and away from said ram member and said wedge-shaped supporting members transverse to said ram member.
9. In a press of the class described, a vertically movable hydraulically operable ram member; a valve device for controlling the movement of said ram member; a lower platen arranged above and movable relative to said ram member; a fixed upper platen arranged above said lower platen; mechanically operated supporting means movable transverse to said ram and in between the upper end thereof and the under side of said lower platen, for supporting said platen in its uppermost position; and a rotatable cam member adapted to operate said lower platen, said supporting means and said valve device.
10. In a press of the class described, a vertically movable ram member; a lower platen arranged above and movable relative to said ram member; a fixed upper platen arranged above said lower platen; mechanically operable supporting members movable transverse to said ram and in between the upper end thereof and the under side of said lower platen, for supporting said platen in its uppermost position; and a rotatable cam operatively associated with said supporting members to move them as aforesaid.
11. In a press of the class described, a vertically movable ram member; a lower platen arranged above and movable relative to said ram member; a fixed upper platen arranged above said lower platen; mechanically operable wedge-shaped supporting members movable toward and from one another transverse to said ram and in between the upper end thereof and the under side of said lower platen, for supporting said platen in its uppermost position.

permost position; and a rotatable cam operatively associated with said supporting members to move them as aforesaid.

12. In a press of the class described, a vertically movable ram member; a fixed upper platen; a vertically movable lower platen located between said ram member and said upper platen; supporting members located between said ram member and said lower platen and movable into positions to support said lower platen in its uppermost position, and to permit downward movement thereof into its lowermost position; means carried by said ram member for moving said lower platen and said supporting members as aforesaid; and a rotatable cam operatively associated with said means for operating the same.

13. In a press of the class described, a vertically movable hydraulically operable ram member; a fixed upper platen; a vertically movable lower platen located between said ram member and said upper platen; wedge-shaped supporting members located between said ram member and said lower platen and movable transverse to said ram member into positions to support said lower platen in its uppermost position, and to permit downward movement thereof into its lowermost position; means carried by said ram member for moving said lower platen vertically and said supporting members transverse to the ram member as aforesaid; a valve device for controlling the movement of said ram member; and a rotatable cam adapted to operate the means aforesaid which is carried by the ram member and to also operate said valve device, said cam having a groove in one of its sides for operating said means and a groove in its opposite side for operating said valve device.

14. In a press of the class described, a vertically movable hydraulically operable ram member; a fixed upper platen; a vertically movable lower platen located between said ram member and said upper platen; supporting means carried by said ram member and arranged between the same and said lower platen and movable into positions to support said lower platen in its uppermost position, and to permit downward movement thereof into its lowermost position; means carried by said ram member for moving said lower platen and said supporting means as aforesaid; a valve device for controlling the movement of said ram member; and a rotatable cam operatively associated with the means aforesaid which is carried by the ram member and which cam also operates said valve device.

15. In a press of the class described, a vertically movable hydraulically operable ram member, a fixed upper platen; a vertically movable lower platen located between said ram member and said upper platen; wedge-shaped supporting members carried by said ram member and located between the same and said lower platen, and movable transverse to said ram member into positions to support said lower platen in its uppermost position, and to permit downward movement thereof into its lowermost position; means carried by said ram member for moving said

lower platen and said supporting members as aforesaid; a valve device for controlling the movement of said ram member; and a rotatable cam adapted to operate the means aforesaid which is carried by the ram member, and which cam also operates said valve device.

16. In a press of the class described, a vertically movable hydraulically operable ram member; a fixed upper platen; a vertically movable lower platen located between said ram member and said upper platen; wedge-shaped supporting members carried by said ram member and located between the same and said lower platen, and movable transverse to said ram member into positions to support said lower platen in its uppermost position, and to permit downward movement thereof into its lowermost position; means carried by said ram member for moving said lower platen vertically and said supporting members transverse to the ram member as aforesaid; a valve device for controlling the movement of said ram member; and a rotatable cam adapted to operate the means aforesaid which is carried by the ram member and to also operate said valve device, said cam having a groove in one of its sides for operating said means and a groove in its opposite side for operating said valve device.

17. In a press of the class described, a vertically movable ram member having inclined surfaces upon its upper side; a vertically movable lower platen located above said ram member and having a plurality of ribs upon its under side; means for moving said lower platen upward and away from said ram member; wedge-shaped supporting members resting upon the inclined surfaces of said ram member and movable toward and from one another, and having supporting ribs upon their upper sides adapted to lie beneath the ribs of the platen to thereby support the same in its uppermost position; and means for moving said supporting members and said lower platen as aforesaid.

18. In a press of the class described, a vertically movable ram member having inclined surfaces upon its upper side; a vertically movable lower platen located above said ram member and having a plurality of ribs upon its under side; wedge-shaped supporting members resting upon the inclined surfaces of said ram member and movable toward and from one another, and having supporting ribs upon their upper sides adapted to lie beneath the ribs of the platen to thereby support the same in its uppermost position; mechanically operated means carried by said ram member for moving said supporting members and said lower platen as aforesaid; and a rotatable cam operatively associated with said last mentioned means.

19. In a press of the class described, a vertically movable hydraulically operable

ram member having inclined surfaces upon its upper side; a vertically movable lower platen located above said ram member and having a plurality of ribs upon its under side; wedge-shaped supporting members resting upon the inclined surfaces of said ram member and movable toward and from one another, and having supporting ribs upon their upper sides adapted to lie beneath the ribs of the platen to thereby support the same in its uppermost position; mechanically operated means carried by said ram member for moving said supporting members and said lower platen as aforesaid; 15 a valve device for controlling the movement of said ram member; and a single rotatable cam operatively associated with said last mentioned means and with said valve device.

20. In a press of the class described, a fixed upper platen; a vertically movable lower platen having a plurality of ribs upon its under side; a vertically movable ram member located below said lower platen and having inclined surfaces upon its upper side; means for moving said lower platen upward and away from said ram member; cooperating guide members carried by said fixed and movable platens for guiding the latter in its movements; wedge-shaped supporting members resting upon the inclined surfaces of said ram member and movable toward and from one another, and having supporting ribs upon their upper sides adapted to lie beneath the ribs of the lower platen to thereby support the same in its uppermost position; and means for moving said supporting members and said lower platen as aforesaid.

21. In a press of the class described, a fixed upper platen; a vertically movable lower platen; a vertically movable ram member located below said lower platen and having inclined surfaces upon its upper side; means for moving said lower platen upward and away from said ram member; cooperating guide members carried by said fixed and movable platens for guiding the latter in its movements; wedge-shaped supporting members resting upon the inclined surfaces of said ram member and movable toward and from one another and adapted to support said lower platen in its uppermost position; and means for moving said supporting members and said lower platen as aforesaid.

22. In a press of the class described, a vertically movable ram member; a vertically movable lower platen located above and movable relative to said ram member; two mechanically operable supporting members located between said ram member and said platen for supporting the same in its uppermost position from said ram member, and for permitting said platen to move into its lowermost position; and four lifting members carried by said ram member and acting upon the

four corners of said platen to move the same upward and away from said ram member.

23. In a press of the class described, a vertically movable ram member; a vertically movable lower platen located above and movable relative to said ram member; four pivotally supported oscillating levers carried by said ram member; means whereby the upper ends of said levers act upon the four corners of said lower platen to move it upward and away from said ram member; wedge-shaped supporting members carried by said ram member and movable toward and from one another between said ram member and said lower platen, and acting to support the same in its uppermost position; means whereby said supporting members are operated by said levers; a rotatable main cam member; and means whereby said levers are operated by said cam member.

24. In a press of the class described, a vertically movable ram member having oppositely inclined upper surfaces; a vertically movable lower platen located above and movable relative to said ram member, and having a plurality of parallel supporting ribs upon its under side; four lifting members secured one to each corner of said platen and having each a cam groove; four pivotally supported oscillating levers carried by said ram member; rollers at the upper ends of said levers and which operate in the grooves aforesaid to move said platen upward and away from said ram member; two wedge-shaped supporting members movable upon the inclined surfaces aforesaid toward and from one another, and which have ribs upon their upper sides which lie beneath the ribs of said platen when the same is in its uppermost position; pins at the upper ends of said levers extending into holes at the outer ends of said supporting members and whereby said members are moved as aforesaid; and means for operating said levers.

25. In a press of the class described, a vertically movable ram member having inclined surfaces upon its upper side; a vertically movable lower platen located above and movable relative to said ram member, and having a plurality of parallel supporting ribs upon its under side; four cam members secured one to each corner of said platen; four pivotally supported oscillating levers carried by said ram member; rollers at the upper ends of said levers which act upon said cams to move said platen upward as aforesaid; two wedge-shaped supporting members movable upon the inclined surfaces of said ram member and transverse thereto, and which have ribs upon their upper sides which lie beneath the ribs of said platen when the same is in its uppermost position; means whereby said supporting members are operated by and from said levers; and a rotating main operating cam whereby said levers are operated.

26. In a press of the class described, a fixed upper platen; a lower platen movable toward and from said upper platen to close and open the press; a piston acting upon said platen to move it upward; a cylinder wherein said piston moves; a valve device for controlling the supply of liquid under pressure to said cylinder, and for relieving the pressure in said cylinder and permitting slight downward movement of said platen; means for operating said valve device; and means permitting said valve device to be operated when the press is open to permit outflow of liquid from said cylinder and movement of the piston therein downward to a greater extent than it moves when the pressure in the cylinder is relieved. 70
27. In a press of the class described, a fixed upper platen; a lower platen movable toward and from said upper platen to close and open the press; a piston acting upon said platen to move it upward; a cylinder wherein said piston moves; a valve device for controlling the supply of liquid under pressure to said cylinder, and for relieving the pressure in said cylinder and permitting slight downward movement of said platen; a rotating cam for operating said valve device automatically to cause the press to operate in accordance with a definite and predetermined cycle; and means permitting said valve device to be operated manually, but only when the press is open, to permit outflow of liquid from said cylinder and movement of the piston therein downward to a greater extent than it moves when the pressure in the cylinder is relieved. 75
28. In a press of the class described, a fixed upper platen; a lower platen movable toward and from said upper platen to close and open the press; a piston acting upon said platen to move it upward; a cylinder wherein said piston moves; a valve device for controlling the supply of liquid under pressure to said cylinder, and for relieving the pressure in said cylinder and permitting slight downward movement of said platen; an operating member for said valve device, the same having a roller for operating it; and a rotating cam having a groove into which said roller extends and wherein it runs; said groove having a long portion of constant radius which acts to operate the valve device to admit liquid under pressure to the cylinder, a projection for operating the valve device for a short time to relieve the pressure in the cylinder, and a portion which is wider than the rest of the groove and in which the roller is when the press is open, and during which time the valve device may be operated manually to permit further downward movement of the piston. 80
29. In a press of the class described, a fixed upper platen; a lower platen movable toward and from said upper platen to close and open the press; a ram member acting upon said lower platen to move it upward; a piston for moving said ram member upward, said piston being separated from said ram member and movable downward independently thereof; a cylinder wherein said piston moves; a valve device for controlling the supply of liquid under pressure to said cylinder, and for relieving the pressure in said cylinder and permitting slight downward movement of said ram member and lower platen; means for operating said valve device; and means permitting said valve device to be operated when the press is open to permit outflow of liquid from said cylinder and movement of said piston downward independently of said ram member. 85
30. In a press of the class described, a bracket having a cam supporting pin extending therefrom; a driving gear and a main operating cam secured together to move in unison, and which are together rotatable upon said pin; a main driving shaft, one end of which is supported in a bearing in said bracket; two plates supported by said bracket and which are spaced apart from one another; a driving pinion upon the end of said shaft and between said plates; two oppositely arranged bearings one in each of said plates; and an idle gear supported from said two bearings, and through which gear said pinion acts to drive said driving gear. 90
